PUZZLE OR SIMILAR ARTICLE

Jane L. Brown, 1360 W. Granada Court,
Ontario, Calif. 91762

Filed May 27, 1971, Ser. No. 147,728

Term of patent 14 years

Int. Cl. D21—01

U.S. Cl. D34—15

FIG. 1 is a side elevational view of one side of the puzzle, showing my new design.

FIG. 2 is a front elevational view thereof.

FIG. 3 is a side elevational view of the other side thereof.

FIG. 4 is a top plan view thereof.

FIG. 5 is a bottom plan view thereof.

I claim:

The ornamental design for a puzzle or similar article, substantially as shown and described.
